WILSON R. VOORHEES, OF PERTH AMBOY, NEW JERSEY.

MAXIMUM-SPEED GOVERNOR FOR AUTOMOBILES.

1,302,251.

Specification of Letters Patent. Patented Apr. 29, 1919.

Application filed February 16, 1918. Serial No. 217,557.

To all whom it may concern:

Be it known that I, WILSON R. VOORHEES, a citizen of the United States, residing at Perth Amboy, in the county of Middlesex and State of New Jersey, have invented a new and useful Maximum-Speed Governor for Automobiles, of which the following is a specification.

This invention has reference to maximum speed governors for automobiles, and its object is to provide an attachment which may be applied to the carbureter of the explosion engine of an automobile, whereby the vehicle may be prevented from attaining more than a predetermined maximum speed.

The invention comprises an attachment interposable between the carbureter and intake manifold of the explosion engine, which attachment includes a valve, and has connections to the carbureter whereby suction therein produced tends to close the valve and so throttle the intake to the engine. The arrangement is such that the vehicle may start and attain a certain speed, but beyond such speed the suction of the engine is effective to actuate the throttle and cut down the intake to an extent to prevent the engine from exceeding the desired speed.

The invention is particularly useful in connection with vehicles where the drivers are employees liable to exceed the desirable speed, which speed may be determined by traffic regulations. With the invention, full power may be obtained up to the predetermined speed, but such speed cannot be exceeded, wherefore the vehicle owner is not open to penalization by the speeding of the vehicles under the control of irresponsible or careless drivers.

The invention will be best understood from a consideration of the following detailed description, taken in connection with the accompanying drawing forming part of this specification, with the further understanding that, while the drawing shows a practical form of the invention, the latter is not confined to any strict conformity with the showing of the drawings but may be changed and modified so long as such changes and modifications come within the scope of the appended claims.

In the drawing:—

Figure 1 is an elevation of the cylinders and carbureter of an automobile engine with the invention applied;

Fig. 2 is a side elevation of the attachment

separate from the carbureter, and showing it as seen from the opposite side to that viewed in Fig. 1, the showing being on a larger scale than that shown in Fig. 1; 60

Fig. 3 is a section on the line 3—3 of Fig. 1, with distant parts omitted, but drawn on the scale of Fig. 2;

Fig. 4 is a section on the line 4—4 of Fig. 3; 65

Fig. 5 is a section on the line 5—5 of Fig. 3.

Referring to the drawings, there is shown in Fig. 1 an outline representation of an explosion engine 1, such as may be found upon an automobile, and the showing of the engine may be considered as representative of any suitable automobile engine, or in fact, of any explosion engine to which the invention is applicable. There is also shown in Fig. 1 a carbureter 2, which may be considered as of known type and indicative of any suitable type of carbureter adapted for the purposes of the present invention. No detailed description is given of either the engine or the carbureter, and mention is made of parts of both the engine and carbureter only in so far as is necessary for an understanding of the invention. 75

Between the manifold 3 of the engine, and the main conduit 4 of the carbureter, there is located a coupling 5 provided with terminal flanges 6 introduced between the usual flanges 7 and 8 on the manifold and carbureter respectively. The coupling 5 forms 80 part of the attachment, and is of sufficient length to inclose a valve 9 shown as of the butterfly type, and of a size to substantially close the passage through the coupling when the valve is transverse thereof. Journaled 85 in opposite sides of the coupling 5 is a shaft 10 carrying the valve 9. At one side of the coupling is an extension 11, inclosing part of a chamber 12, the remainder of the chamber comprising a cap 13 made fast to the extension 11 by screws 14 or otherwise. The extension 11 may be in one piece with the coupling 5, and the coupling with its extension as well as the cap 13 may be in the form of castings. The cap 13 is made separate from the extension 11 to permit access to the interior of the chamber 12. At one end, the extension 11 and cap 13 have cylindrical matching portions 15 gripping a neck 16 on one end of a cylinder 17, thereby holding the cylinder in place, the gripping being accomplished by screws 18 similar to the screws 14. 100 105 110

The cylinder 17 is provided at the end remote from the neck 16 with a head 19 indicated as screwed on the cylinder, but it will be understood that the head 19 may be otherwise secured. Within the cylinder there is located a piston 20 fast at one end to a piston rod 21 in turn connected to a crank 22 within the chamber 12 and fast to the shaft 10. The piston 20 is made to fit snugly yet 10 freely in the cylinder 17, since it is not obligatory that the fit be a gas-tight one.

Within the cylinder 17 on the side of the piston remote from the piston rod, there is a spring 23 at one end bearing against the 15 piston and at the other end bearing against a plate 24 also within the piston. The plate 24 has perforations 25 therethrough, and is engaged by a screw 26 threaded through the head 19 to the exterior thereof for manipulation to adjust the plate 24 lengthwise of the cylinder to vary the pressure of the 20 spring 23 upon the piston 20. Connected to the interior of the cylinder through the head 19 by a coupling 27 is a pipe 28, leading to the duct 4 of the carbureter, to which duct the pipe is connected by a coupling 29 or in 25 any other suitable manner, the arrangement being such that the pipe 28 communicates with the carbureter near the outlet end of 30 the latter.

In order to prevent the formation of air or gas cushions within the chamber 12, passages 30 are bored through a suitable portion of the coupling 5 so as to come close to the 35 shaft 10 in a direction about perpendicular to the length of the shaft, and at another point, other holes 31 are bored in intersecting relation to the first-named holes to communicate with the atmosphere, those holes 40 close to the shaft being plugged at their outer ends so that access may not be had directly to the shaft as would occur if the outer ends of the holes 30 were not plugged. The fit between the shaft 10 and its bearings 45 adjacent to the chamber 12 is sufficiently loose to permit ample air leakage between the passages 30 and the chamber 12.

In order to prevent any tampering with the adjustments of the device, the screw 26 50 has a hole 32 bored through the head thereof, and the coupling 27 is provided with an ear 33 with a hole 34 bored therein. This permits the passage of a wire 35 through the holes to be connected by a seal 36, whereby 55 unauthorized change in the adjustment is prevented. Similar arrangements may be made in the structure wherever parts can be removed and adjustments varied.

When a vehicle equipped with the invention 60 is intrusted to an employee for operation, the employer can be assured that a certain speed limit will not be exceeded by the proper adjustment of the attachment. Then when the driver of the vehicle speeds 65 up, the suction produced by the engine will

establish vacuum conditions through the pipe 28 to the corresponding side of the piston 20, which vacuum conditions when the predetermined limit is reached, cause a movement of the piston 20 in opposition to the 70 holding power of the spring 23. This results in a turning of the valve 9 through the piston rod 21, crank 22 and shaft 10, to close the passage through the coupling 5 to an extent depending upon the degree of suction 75 established. The parts may be adjusted so that when the critical vacuum conditions are reached, the spring 23 will yield rapidly and shut down the supply of fuel to an extent to prevent any further increase of 80 speed or even to compel the operator to purposely reduce the speed in order to maintain the necessary power to run the vehicle. Under such circumstances, an operator will not attempt to exceed the fixed speed limit, since 85 such attempt must only result in failure. In this manner, the device is protective of the interests of the owner of the vehicle who must intrust it to others to operate, and the liability of the owner for injuries due to the 90 carelessness or disobedience of the operators due to excessive speed is entirely avoided. Even if the operator be inclined to change the adjustments in order to attain higher speed, such change cannot be brought about 95 without detection, because of the sealing of all places where access to the adjustments might be had to the extent of changing it.

What is claimed is:—

1. An attachment for explosion engines 100 for limiting the speed at which the engine may be run by an operator, comprising a coupling for location between the carbureter and the intake manifold of the engine, a valve in the passage through the coupling, 105 pressure-responsive means connected to the valve, connections between the suction side of the carbureter and that side of the pressure-responsive means remote from the valve, and an inclosure for the pressure-responsive means and the connections sealed when in use against unauthorized access, 110 whereby when the attachment is set an operator of the engine cannot run the latter above a predetermined speed. 115

2. An attachment for explosion engines for positively limiting the speed at which the engine may be run by an operator, comprising a valve for introduction into the fuel conduit between the carbureter and engine, 120 pressure-responsive means connected to the valve, a casing wholly inclosing the pressure-responsive means against access, and means for adjusting the pressure-responsive means and provided with means whereby 125 the adjusting means may be sealed against unauthorized manipulation.

3. An attachment for explosion engines for establishing a predetermined limit at which the engine may be run by an operator, com- 130

prising means for controlling the amount of fuel directed to the engine, pressure-responsive means connected to the controlling means to cause the latter to act when the 5 desired speed limit has been attained, and means for sealing against unauthorized manipulation all parts of the attachment through which change of adjustment may be effected, whereby the attachment when 10 installed and adjusted is proof against the running of the engine above a predetermined speed.

4. Means for establishing a predetermined limit at which an explosion engine may be 15 run by an operator, comprising a casing having a fuel duct introducible between the carbureter and intake manifold of the explosion engine, means for controlling the amount of fuel passing from the carbureter 20 to the intake manifold, actuating means for said controlling means responsive to the suction of the engine and completely housed within the casing against access, and regulating means for the actuating means accessible at the exterior of the casing and constructed to be sealed against manipulation.

5. An attachment for explosion engines for limiting the speed by controlling the fuel directed to the engine, comprising a 30 coupling for interposition between and connecting a carbureter to the manifold of the explosion engine, a valve in the coupling for controlling the flow of fuel from the carbureter to the manifold, a chamber structure 35 carried by the coupling, a cylinder carried by the chamber structure and communicating therewith, a crank shaft carrying the valve and having its crank end within the chamber, a piston rod extending into 40 the chamber and connecting the crank and piston, a spring engaging the piston on the

side remote from the piston rod, a movable plate engaging the spring, an adjusting screw engaging the plate, a head for the cylinder carrying the screw, and a pipe communicating with the cylinder through said head and arranged to be coupled to the carbureter adjacent to the outlet end thereof. 45

6. An attachment for explosion engines for limiting the speed by controlling the fuel directed to the engine, comprising a coupling for interposition between and connecting a carbureter to the manifold of the explosion engine, a valve in the coupling for controlling the flow of fuel from the carbureter to the manifold, a chamber structure carried by the coupling, a cylinder carried by the chamber structure and communicating therewith, a crank shaft carrying the valve and having its crank end 55 within the chamber, a piston rod extending into the chamber and connecting the crank and piston, a spring within the cylinder and engaging the piston on the side remote from the piston rod, a movable plate also 60 within the cylinder and engaging the spring, an adjusting screw engaging the plate, a head for the cylinder carrying the screw, and a pipe communicating with the cylinder through said head and arranged to be 65 coupled to the carbureter adjacent to the outlet end thereof, said coupling having tortuous air passages between the chamber and the atmosphere. 70

In testimony that I claim the foregoing as 75 my own, I have hereto affixed my signature in the presence of two witnesses.

WILSON R. VOORHEES.
